FIG. 2 is a rear isometric view of the holding device of FIG. 1.

FIG. 3 is a front elevation view of the holding device of FIG. 1.

FIG. 4 is a rear elevation view of the holding device of FIG. 1.

FIG. 5 is a right elevation view of the holding device of FIG. 1.

FIG. 6 is a left elevation view of the holding device of FIG. 1.

FIG. 7 is a top plan view of the lid holding device of FIG. 1.

FIG. 8 is a bottom plan view of the holding device of FIG. 1.

FIG. 9 is a front isometric view of a second embodiment of a holding device for a cooking container lid.

FIG. 10 is a rear isometric view of the holding device of FIG. 9.

FIG. 11 is a front elevation view of the holding device of FIG. 9.

FIG. 12 is a rear elevation view of the holding device of FIG. 9.

FIG. 13 is a right elevation view of the holding device of FIG. 9.

FIG. 14 is a left elevation view of the lid holder of FIG. 9.

FIG. 15 is a top plan view of the lid holder of FIG. 9.

FIG. 16 is a bottom plan view of the lid holder of FIG. 9.

FIG. 17 is a front isometric view of a third embodiment of a holding device for a cooking container lid.

FIG. 18 is a rear isometric view of the holding device of FIG. 17.

FIG. 19 is a front elevation view of the holding device of FIG. 17.

FIG. 20 is a rear elevation view of the holding device of FIG. 17.

FIG. 21 is a right elevation view of the holding device of FIG. 17.

FIG. 22 is a left elevation view of the holding device of FIG. 17.

FIG. 23 is a top plan view of the holding device of FIG. 17.

FIG. 24 is a bottom plan view of the holding device of FIG. 17.

FIG. 25 is a front isometric view of a fourth embodiment of a holding device for a cooking container lid.

FIG. 26 is a rear isometric view of the holding device of FIG. 25.

FIG. 27 is a front elevation view of the holding device of FIG. 25.

FIG. 28 is a rear elevation view of the holding device of FIG. 25.

FIG. 29 is a right elevation view of the holding device of FIG. 25.

FIG. 30 is a left elevation view of the holding device of FIG. 25.

FIG. 31 is a top plan view of the holding device of FIG. 25; and,

FIG. 32 is a bottom plan view of the holding device of FIG. 25.

The broken lines shown in FIG. 1 are for illustrative purposes only and are not part of the claimed design.
